[57] **CLAIM**

The ornamental design for a hat jewelry box with tassel, as shown and described.

DESCRIPTION

FIG. 1 is a perspective view of a hat jewelry box with tassel, showing my new design;

FIG. 2 is a perspective view shown with the lid in an open position and the tassel shown shifted to a new position (beside the hinge), and the end of the tassel slightly raised; FIG. 3 is a top plan view shown with the lid in a closed position;

FIG. 4 is a front elevation view thereof;

FIG. 5 is a bottom plan view thereof;

FIG. 6 is a left side elevation view thereof;

FIG. 7 is a rear elevation view thereof; and,

FIG. 8 is a right side elevation view thereof.
